UNITED STATES PATENT OFFICE.

IRA E. SARBER, OF ELMORE, ALABAMA.

DESIGN FOR A GRAVE COVER OR SIMILAR ARTICLE.

Application filed April 5, 1928. Serial No. 26,134. Term of patent 14 years

To all whom it may concern:

Be it known that I, IRA E. SARBER, a citizen of the United States, residing at Elmore, in the county of Elmore, and State of Alabama, have invented a new, original, and ornamental Design for a Grave Cover or Similar Article, of which the following is a specification, reference being had to the accompanying drawing, forming part thereof.

The drawing illustrates a view in perspective of a grave cover or similar article embodying my design.

I claim:

The ornamental design for a grave cover or similar article, as shown.

IRA E. SARBER.
